ROTARY RADIO ANTENNA ELEMENT

Robert Alan Cowdery, Geneva, and Howard L. Jenkins, Springfield, Ohio, assignors to The American Fork & Hoe Company, Cleveland, Ohio, a corporation of Ohio

Application September 16, 1939, Serial No. 295,260

5 Claims. (Cl. 250—33)

Our invention relates to improvements in radio antennae and relates particularly to improvements in antennae for radio broadcasting purposes.

An object of our invention is to provide elements for use in radio antennae whether used for transmitting or receiving purposes.

Another object of our invention is to provide improved elements for radio antennae of the rotary beam type.

Another object of our invention is to provide improved elements for radio antennae whereby such elements can more efficiently transmit energy.

Another object of our invention is to provide improved elements for radio antennae which can be used in multiple form for use in the transmission of what are commonly known as directive beams.

Another object of our invention is to provide improved elements for radio antennae so constructed as not to be susceptible to sway responsive to wind effects.

Another object of our invention is to provide an improved radio antenna element in the form of a metallic rod which is adapted to be horizontally disposed, secured by one end only in straight form.

Another object of our invention is to provide improved elements for radio antennae of the type referred to wherein several elements may be mounted close together and whereby the supporting element may be relatively small in extent.

Another object of our invention is to provide an improved jointed element for radio antennae.

Other objects of our invention and the invention itself will become apparent by reference to the attached drawing and the description appended hereto.

In the drawing:

Fig. 1 is a view of an assembled radio antenna comprising several of the elements of our invention;

Fig. 2 is a view of an antenna element of our invention;

Fig. 3 is a view of the element of Fig. 2 showing the amount of gravity sag which ordinarily would take effect and which has been predetermined according to the specific dimensions of the element and the type of mounting which will be employed;

Fig. 4 shows the element of Fig. 2 in its operative pre-bent relation;

Fig. 5 is a view of a coupling for several spliced sections of the element, and

Fig. 6 is a view of several spliced sections of the

element of Fig. 2 showing another embodiment of the coupling.

It will be noted that certain dimensions are employed in connection with the various figures of drawing and it is further to be noted that these dimensions are optional but that they are used to show the relative proportions of the element and the degree of pre-bending which is necessary in order to take up any gravity sag which would occur in a straight tapered tube, such as is shown in the drawing.

The radio antenna of our invention is composed of several elements which are preferably supported at one end. Since antenna elements are merely supported at one end, a certain amount of dip or bend in a downward direction occurs in each element of my invention, whether it be composed of one or several component parts, which must be compensated for. Each element of our invention may be either a straight tube composed of one or several parts or a tapered tube of any preferred degree of taper and composed of one or several parts.

In the drawing, we have shown in Figs. 1, 2, 3 and 4 a tapered tube which is composed of three component parts, these parts being designated, for the purposes of this description, as 1, 2 and 3. In Fig. 1, a pair of these are shown mounted in alignment on a support 8 having insulators 4, 5, 6 and 7 connecting the same with the elements. In other words, each element, whether it be the right hand element designated as A, or the left hand element designated as B, are supported by means of the support 8 and are mounted on a pair of insulators, whether it be the insulators 6 and 7, or 4 and 5 extending upwardly from the support.

The elements are generally intended for use as directional antenna arrays and usually extend outwardly from the support a distance of 15 to 18 feet although this is a matter of design and not essential. It is to be noted that the present elements each have an overall length of 16' 10" from the support end to the tip. Those portions of the antenna 1 and 2, and 1' and 2' which are closest to the mounting portion are substantially of equal length and the tip portions 3 and 3' are of relatively shorter length and considerably reduced diameter. The reduction shown on Fig. 1 of the drawing herein for the entire given length of the tube of 16' 10" is approximately .532" from the support end to the tip. The reduction, however, is gradual and is, in the form shown, preferably greater at the end of the first portion

of the tube than the end of the middle portion or in the last third of the tube length.

It is to be noted in the form shown that the portion extending over approximately the first third of the total length of the tube shows no reduction in diameter; this is the portion of the element which is supported for a considerable extent by the main support by means of the insulators. The tube is reduced prior to its point of juncture with the next tube element, as shown in Fig. 2, however, and the reduced end of the second section is telescoped within the slightly larger diameter of the end of the first section, the end of the first tube section being screw threaded and adapted to have threaded engagement with a screw threaded portion carried by the second section. The end tube section is, in turn, of still less diameter than the second section and is adapted to have threaded engagement therewith in the manner shown in either Figs. 5 or 6.

Obviously however, any desired wall thickness throughout the length of the antenna element could be employed and any desired degree of taper. Further, the element could be of uniform outer diameter throughout with a uniform wall thickness. Our preferred embodiment, however, constitutes a sectional tapered tube of decreased wall thickness towards the tip portion the principal purpose of our invention being the pre-bending of the antenna element before it is adapted for use in its preferred mounting.

Fig. 4 of the drawing shows the amount of pre-bending in a tube having the proportions shown in Fig. 2. This has been calculated in view of the amount of drop or downward bend or sag which the element of Fig. 2 assumes when the same is mounted, as shown in Fig. 1, Fig. 3 illustrating the amount of dip or bend which will occur in the element due to the force of gravity.

It is to be noted that in the practice of our invention we first ascertain the amount of bend which will or may occur and compensate for the same by pre-bending the element in the proportionate amount in the reverse direction.

In Fig. 4, for instance, this is shown as being an upward bend, then when the element is mounted at one end with the bend upwardly of the tube, as in Fig. 1, the element due to gravity will assume a substantially horizontal position. It will be readily understood that the mounting structure can thence be comparatively short and the wind resistance thus reduced.

It will also be readily understood that the transmission of energy will be of increased efficiency. The principle of pre-bending the tube as described herein may be applied to correct any other force besides gravity which might ordinarily be applied to the element when in use and which would tend to cause swinging such as wind pressure or the like. The elements of our invention may be either tubular or solid, tapered or straight, and may be made of any kind of metal.

Although we have shown and described a preferred embodiment of our invention, we contemplate that numerous and extensive departures may be made therefrom without departing from

the spirit of our invention and the scope of the appended claims.

We claim:

1. An antenna element in the form of a rod adapted to be mounted solely at one end thereof, said antenna being mounted in a horizontal position and prior to mounting being prebent to compensate for a predetermined downward droop when the element is in operative mounted horizontal position whereby the element will assume a substantially straight form in the mounted position responsive to the effect of gravity thereon.
2. A multiple beam antenna comprising a plurality of antenna elements, said elements each being in the form of a rod and adapted to be mounted solely at one end thereof and to be disposed in substantial axial alignment with each other and in a generally horizontal position, said elements prior to mounting being prebent to compensate for a predetermined downward droop when the element is in operative mounted horizontally disposed position whereby the element will assume a substantially straight form in the mounted position responsive to the effect of gravity, said elements being maintained in substantially parallel relation to each other.
3. In combination, a support, a pair of spaced insulators mounted upon said support and an antenna element having one end fixedly mounted in said insulators, the other end being free, said antenna element being prebent to compensate for a predetermined downward bend when said antenna is in operative mounted position, whereby said insulators may be mounted relatively close together and said antenna element will assume a substantially straight form in the mounted position responsive to the effect of gravity.
4. In combination, a support, a pair of spaced insulators mounted upon said support and an antenna element having one end fixedly mounted in said insulators, the other end being free, said antenna element being in the form of a rod, the portion which rests upon and between said supports being of substantially uniform diameter and the remaining portion being tapered to a relatively smaller diameter, the tapered portion of said antenna prior to mounting being prebent to compensate for a predetermined downward bend when the antenna element is in operative mounted position, whereby the antenna will assume a substantially straight form in the mounted position responsive to the effect of gravity.
5. An antenna element in the form of a tubular rod comprising a plurality of sections, said sections being threaded secured together at their adjacent ends, whereby the length of said antenna element may be accurately adjusted laterally for different frequencies and said antenna element being prebent in the shape of an arc to compensate for a predetermined downward bend of the antenna when the same is in operative mounted position, whereby the element will assume a substantially straight form in the mounted position responsive to the effect of gravity.
